UNITED STATES PATENT OFFICE.

LAWRENCE JOHNSON AND ALFRED N. WENTINK, OF CHICAGO, ILLINOIS; SAID JOHNSON ASSIGNOR TO SAID WENTINK.

INSULATED-WIRE-STRIPPING DEVICE.

Application filed November 5, 1926. Serial No. 146,518.

Our invention relates to devices for stripping insulation from the ends of electrical conductors so that the conductors may be readily secured to the terminals of electrical circuits.

The invention has among its other objects the production of devices of the kind described which are simple in construction, relatively inexpensive to manufacture, compact, convenient, durable and satisfactory for use wherever found applicable.

A particular object of the invention is to provide a device of the kind described which comprises a minimum number of parts and may be mounted upon a work-bench or the like.

One form of the invention is embodied in a device which preferably comprises a one-piece base in which two posts are rotatably journaled, the posts carrying knives which are adjustably secured thereto. The posts are provided with intermeshing gears which co-operate with a spring to yieldably hold the knives in positions wherein they will strip insulation from a wire drawn between them.

Many other objects and advantages of the construction herein shown and described will be obvious to those skilled in the art from the disclosure herein given.

To this end our invention consists in the novel construction, arrangement and combination of parts herein shown and described, and more particularly pointed out in the claims.

In the drawing, wherein like reference characters indicate like or corresponding parts:

Fig. 1 is a plan view of a device embodying the invention;

Fig. 2 is a section taken on line 2—2 of Fig. 1;

Fig. 3 is a bottom plan view of the device shown in Fig. 1;

Fig. 4 is a section taken on line 4—4 of Fig. 1;

Fig. 5 is a section taken on line 5—5 of Fig. 4;

Fig. 6 is a section taken on line 6—6 of Fig. 4; and

Fig. 7 is a fragmentary section corresponding to Fig. 2, and illustrating another form of the invention.

In the drawings we have shown a pre-

ferred form of the invention embodied in a device for stripping insulation from the ends of electrical conductors, the device preferably comprising a one-piece block or base 10 adapted to be mounted upon a work-bench, or the equivalent. For this purpose, the base 10 is provided with counter-sunk holes 12 adapted to accommodate screws whereby the base may be secured to the bench. Rotatably journaled in the base 10 are a pair of vertically disposed posts 14 which carry knives 15 at their upper ends, the knives being slotted as indicated at 16 to accommodate the shanks of screws or bolts 17 whereby the knives are adjustably secured to the posts. Rigidly secured to the lower ends of the posts 14 are gears 18 which mesh with each other, one of the gears being provided with a slot 19 in its periphery, which slot cooperates with a pin 20 projecting from the base to limit angular displacement of the gear and therefore to limit angular displacement of the posts 14 around their respective axes of rotation. A substantially U-shaped spring 23 has its ends secured to the gears 18 by pins or screws 24 and is so constructed that it tends to rotate the gears 18 and the posts 14 into positions wherein the knives 15 will be disposed in positions wherein they are shown in full lines in Fig. 1. Obviously, the posts 14 may be displaced against the action of the spring 23 to bring the knives into positions wherein they are shown in dotted lines in Fig. 1. The gears 18 and the spring 23 are preferably disposed in a recess 10^a provided in the bottom of the base 10 so that they are protected from tools and the like usually found upon a work-bench.

Riveted to the base 10 is a plate 27 which is preferably formed of a relatively hard metal, the plate 27 being so positioned with respect to the knives 15 that an electrical conductor may be guided thereby into the knives.

Adjustably secured to a boss 29 formed integral with the base 10 is a substantially L-shaped gauge 30 provided with a slot 31 through which a screw 32 may be passed to secure the gauge to the boss. As shown, the screw 32 is preferably provided with a knurled head 34 so that it may be easily manipulated.

The operation of the above described de-

vice is substantially as follows: The device is preferably mounted upon a work-bench, or the like, in the manner above described and the knives 15 are adjusted so that the space between them is substantially equal to the diameter of the wire which is to have insulation stripped therefrom. One end of the insulated wire is then passed over the plate 27 and between the knives 15 until it engages the gauge 30, which has been previously adjusted so that insulation will be removed from a predetermined length of wire. When the insulated wire is pushed between the knives 15, the knives rotate into positions wherein they are shown in dotted lines in Fig. 1. The insulated wire is then pulled back between the knives which then bite into the insulation and cut and strip it from the wire.

20 In Fig. 7, we have shown another form of the invention wherein the plate 27 is replaced by a tubular member 35 riveted to the base 10, the tubular member 35 being adapted to guide the ends of insulated wires when they are inserted between the knives 15.

Having thus described our invention, it is obvious that various immaterial modifications may be made in the same without departing from the spirit of our invention; hence we do not wish to be understood as limiting ourselves to the exact form, construction, arrangement and combination of parts herein shown and described or uses mentioned.

We claim:

1. In a device of the kind described and in combination, a base having a recess in the bottom thereof, a pair of vertically disposed posts rotatably journaled in the base, means disposed in said recess for constraining said posts to rotate in unison, and knives carried by the posts.

2. In a device of the kind described and in combination, a base, a pair of vertically disposed posts rotatably journaled in the base, a tooth member on one of said posts, a second tooth member on the other of said posts, said second tooth member meshing with said first-mentioned tooth member, yielding means for rotating said posts into predetermined positions, and knives carried by said posts.

3. In a device of the kind described and in combination, a base, a pair of vertically disposed posts rotatably journaled in the base, a tooth member on one of said posts, a second tooth member on the other of said posts, said second tooth member meshing with said first-mentioned tooth member, yielding means for rotating said posts into predetermined positions, and knives carried by said posts.

predetermined positions, and knives adjustably secured to said posts.

4. In a device of the kind described and in combination, a base having a recess therein, a pair of posts rotatably journaled in the base, intermeshing tooth members secured to said posts and disposed in said recess, yielding means disposed in said recess for urging said posts in predetermined positions, and knives carried by said posts.

5. In a device of the kind described and in combination, a base having a recess in the bottom thereof, a pair of vertically disposed posts rotatably journaled in the base, means disposed in said recess for constraining said posts to rotate in unison, and knives adjustably secured to said posts.

6. In a device of the kind described and in combination, a base having a recess in the bottom thereof, a pair of vertically disposed posts rotatably journaled in the base, means disposed in said recess for constraining said posts to rotate in unison, knives carried by the posts, and a gauge member adjustably mounted on said base.

7. In a device of the kind described and in combination, a base, a pair of vertically disposed posts rotatably journaled in the base, a tooth member on one of said posts, a second tooth member on the other of said posts, said second tooth member meshing with said first-mentioned tooth member, yielding means for rotating said posts into predetermined positions, knives carried by said posts, and a gauge member adjustably mounted on said base.

8. In a device of the kind described and in combination, a base having a recess in the bottom thereof, a pair of vertically disposed posts rotatably journaled in the base, means disposed in said recess for constraining said posts to rotate in unison, knives carried by the posts, a gauge member adjustably mounted on said base, and means for guiding the wire to be stripped.

9. In a device of the kind described and in combination, a base, a pair of vertically disposed posts rotatably journaled in the base, a tooth member on one of said posts, a second tooth member on the other of said posts, said second tooth member meshing with said first-mentioned tooth member, yielding means for rotating said posts into predetermined positions, knives carried by said posts, a gauge member adjustably mounted on said base, and means for guiding the wire to be stripped.

In testimony whereof we have hereunto affixed our signatures.

LAWRENCE JOHNSON.
ALFRED N. WENTINK.
